GOLF TEE

Filed May 22, 1931

UNITED STATES PATENT OFFICE

WILLIAM VICTOR MCCARRIER, OF WEST SUNBURY, PENNSYLVANIA

GOLF TEE

Application filed May 22, 1931. Serial No. 539,393.

This invention relates to golf tees and has for the primary object, the provision of a device of the above stated character which may be easily and quickly positioned in the ground for supporting a golf ball at varying distances relative to the surface of the ground to suit the wishes of players and which will support the ball against accidental movement, due to wind or other similar causes thereby 10 maintaining the ball in proper position for driving.

Another object of this invention is the provision of a supporting post so constructed as to facilitate the insertion thereof into the 15 ground and which will, due to its construction, be prevented from turning relative to the ground during the use of the device.

A further object of this invention is the provision of a ball supporting arm and means 20 for mounting it to the post which will permit the arm to be positioned horizontally relative to the post and the surface of the ground for supporting a ball in proper position relative to the ground for driving and when struck 25 by a club, the supporting arm may move in the arc of a circle and in a horizontal plane so as not to interfere with or affect the ball leaving the tee, thereby aiding in permitting the ball to maintain a true flight in the direction driven and also permitting the post to 30 remain in its proper position and undisturbed.

A further object of this invention is the provision of means for returning the supporting arm to its initial position after the 35 ball is driven therefrom, thus positioning the arm ready to receive another ball to be driven by another player, permitting the same tee to be used by different players when said players are playing together during a 40 game.

A further object of this invention is the provision of means for holding the arm in a true right angular position relative to the post so as to assure proper positioning of the 45 ball relative to the ground and which will permit the arm to be swung into substantial parallelism with the post when not employing the device and which permits the device to be conveniently placed within the pocket of a player 50 or within the pocket of a golf bag or in any

other place suitable to the wishes or convenience of the player.

A further object of this invention is the provision of a golf tee of the above stated character which will be practically indestructible 55 and capable of efficient use over a long period of time and which will be simple, durable and efficient and which may be manufactured and sold at a comparatively low cost.

With these and other objects in view, this 60 invention consists in certain novel features of construction, combination and arrangement of parts to be hereinafter more fully described and claimed.

For a complete understanding of my invention, reference is to be had to the following description and accompanying drawings, in which

Figure 1 is a top plan view illustrating a 65 golf tee constructed in accordance with my invention and showing the movement of the ball supporting arm when the ball is driven therefrom.

Figure 2 is a side elevation illustrating 70 the device in a folded position.

Figure 3 is a side elevation illustrating the device supporting a ball.

Figure 4 is a fragmentary vertical sectional view illustrating the connection between the 75 supporting arm and the post.

Figure 5 is a fragmentary sectional view illustrating the means for holding the ball supporting arm in a horizontal position relative to the post and capable of permitting said arm to be folded into a substantial parallelism with the post as shown in Figure 2.

Figure 6 is a fragmentary side elevation 80 illustrating the arm in a horizontal position and limited in its movement in one direction by a stop.

Figure 7 is a fragmentary elevational view 85 showing the taper of the post to facilitate the insertion thereof into the ground and adapted to prevent accidental turning of the post while positioned in the ground.

Referring in detail to the drawings, the 90 numeral 1 indicates a supporting post having formed integral with its upper end a head 2 provided with a concave face 3 to facilitate a person in obtaining a firm grip on 100

the head for the purpose of inserting the post in the ground. Should the ground be extremely hard, a golf ball may be positioned in the concave face 3 and by gripping the under faces of the head 2 with the fingers and with the ball engaging the palm of the hand, the insertion of the post in the ground will be greatly facilitated. The other end of the post 1 is sharpened as shown at 4 and is also provided with oppositely disposed flattened faces 5 that extend through the sharpened end 4 for the purpose of facilitating insertion of the post in the ground and to obviate the danger of the post turning in the ground after being once positioned therein.

A sleeve 6 is journaled on the post 1 and is limited in an upward direction on said post by an annular shoulder 7 formed by the differences in diameter between the head and the post. A ferrule 8 is mounted on the post 1 and cooperates with a shoulder 7 in rotatably supporting the sleeve 6. The ferrule 8 is adjustably secured to the post by a set screw 9 and has formed therein a chamber 10 opening outwardly through one end of the ferrule for receiving one end of the sleeve 6 which is reduced to extend into the ferrule and provides an annular shoulder 11 adapted to bear on the upper end of the ferrule. A coiled spring 12 surrounds the post 1 within the chamber 10 and has one end secured to the sleeve 6 as shown at 13 while the opposite end is secured to the ferrule. A stop 14 is carried by the ferrule 8 and engaged by an ear 15 formed integral with the sleeve 6 for the purpose of limiting the rotation of the sleeve 6 on the post and the action of the spring 12 is to normally position the ear 15 against the stop 14.

The ear 15 includes a semi-circular shaped portion 16 having a flattened or straight face 17 at its lower edge and in which is formed a notch 18. A notch 19 is formed in the curved edge of the semi-circular portion 16 and spaced a proper distance from the notch 18 for the purpose of maintaining a ball supporting arm 20 in a position disposed at right angles to the post 1. The semi-circular portion 16 of the ear 15 is apertured to receive a pivot bolt 21 extending through an ear 22 similar in construction to the ear 15 formed integral with the ball supporting arm 20.

The ear 22 has overlapping relation with the ear 15 and is provided with a lug 23 engaging the curved edge of the semi-circular portion 16 of the ear 15. The ear 22 is provided with a slot 24 to receive the pivot pin 21 and the latter is provided with a suitable fastener 25 thereon after passing through the ears for retaining them in assembled position as shown in Figure 5. The slot 24 opens outwardly through the inner face of the ear 22 to form a chamber in which is positioned a coiled spring 26 bearing against the under wall of the slot and the pivot pin 22 for the

purpose of urging the lug 23 into the notch 19. A movement of the arm away from the post 1 will cause the lug 23 to move out of the notch 19 and then swinging the arm toward the post to a position as shown in Figure 2, 70 the lug will engage in the notch 18 with a very slight pressure only sufficient to maintain the arm in the position as shown in Figure 2 so that when desiring to use the device, the arm may be swung at right angles to the post and 75 locked in the stated position by the lug 23 engaging in the notch 19 with considerable force due to the action of the spring 26 thereby effectively locking the arm in a horizontal position or at right angles to the post. 80 By having the flattened edge 17 to the ear 15 will relieve the action of the spring 26 when said arm is moved into substantial parallelism with the post so that the arm can be again swung into horizontal position without first moving it in an endwise direction 85 in order to free the lug 23 from the notch 18.

The free end of the arm 20 has formed thereon an annular ball supporting element 27 having one face concaved to form a seat 90 for the ball as shown in Figure 1.

In operation or when desiring to employ the device for supporting a golf ball, the arm 20 is swung into a position at right angles to the post and locked in the stated position 95 by the lug 23 fitting in the notch 19. The player then inserts the post into the ground to the desired depth by placing the thumb on the head 2 with the post disposed between the index and middle fingers. With the post supported vertically in the ground, and the arm 20 disposed in parallelism with the surface of the ground and in spaced relation thereto so that when the ball is positioned on the seat at the end of the arm it 100 will be supported a proper distance from the ground for driving. It is to be understood that the post is inserted in the ground so that the horizontal position of the arm will be at right angles to the direction in which 105 the ball is to be driven and when the ball is struck by the club, there is a possibility that the club may also strike the ball seat on the arm and due to this force, the arm will swing in the arc of a circle to prevent 110 disturbing the post in the ground and also to offer practically no resistance to the ball when leaving the seat thereby permitting the ball to travel in a true course or in the direction driven without affecting or influencing 115 the ball in any way. After the ball leaves the seat on the arm and said arm reaches the limit of its movement due to the club striking the seat and the ball leaving said seat, 120 said arm is automatically returned to its initial position by the influence of the spring 26, ready to receive another ball, thus it will be seen that several persons playing a game together may use the same tee without the necessity of adjusting or replacing the tee 125 130

in the ground after each time a ball is driven therefrom. Any tendency for the post 1 to turn in the ground is retarded by the flattened faces 5 thereby assuring the post remaining in its proper position in the ground during the use or the driving of the ball from the ball supporting arm. The principle involved in this tee may also be applied to a fixed or stationary tee, that is, a tee which 10 remains in the ground for driving over grounds and the like.

By having the ferrule 8 adjustably secured to the post provides means whereby the frictional engagement of the sleeve 6 relative 15 to the shoulders 7 and 11 may be varied and permits wear between said shoulders and the ends of the sleeve to be compensated for and also permits the tension of the spring 12 to be varied.

20 The device is constructed from any suitable material and preferably from a good grade of metal so that the device is capable of withstanding severe wear and permits the use of the device over a long period of time.

25 While I have shown and described the preferred embodiment of my invention, it will be understood that minor changes in construction, combination and arrangement of parts may be made without departing from the 30 spirit and scope of my invention as claimed.

Having thus described my invention, what I claim is:

1. A golf tee comprising a post adapted to be inserted in the ground to a desired 35 depth, means associated with the post for supporting the ball laterally of the post and in spaced relation to the ground and capable of moving in the arc of a circle when the ball is driven therefrom, and means for returning 40 said first means to its initial position after its movement, before described.

2. A golf tee comprising a post to be inserted in the ground, a sleeve journalled on the post, an ear on said sleeve, a second ear 45 pivotally and slidably connected to the first ear, a ball supporting arm carried by the second named ear, said first named ear having spaced notches, a lug on the arm to engage in either of said notches for supporting the 50 arm at right angles to the post or in substantial parallelism with said post, and tension means for causing the lug to ride against the edge of the first named ear and to engage in said notches when aligned therewith.

55 3. A golf tee comprising a post to be inserted in the ground, a head on said post, a ferrule adjustably secured to the post, a sleeve journalled on the post between the head and ferrule and limited in an endwise 60 movement on said post by the head and ferrule, a ball supporting arm pivotally secured to the sleeve, and means for holding the arm either in a horizontal position relative to the post or in substantial parallelism with 65 the post.

4. A golf tee comprising a post to be inserted in the ground, a head on said post, a ferrule secured to the post, a sleeve journalled on the post and bearing against the head and ferrule, a ball supporting arm carried by said sleeve and adapted to support the ball laterally of the post, a stop carried by said ferrule, tension means connected with the sleeve and post to resist the movement of the arm in one direction and to return said 75 arm when moved in one direction to its initial position, and a stop for limiting the movement of the arm in one direction.

In testimony whereof I affix my signature.
